H. C. BADY

WATER TUBE BOILER

Filed Dec. 8, 1923

Inventor
Henry Charles Bady
by his Attorney
John O. Neal

UNITED STATES PATENT OFFICE.

HENRY CHARLES BADY, OF HOBOKEN, NEW JERSEY.

WATER-TUBE BOILER.

Application filed December 8, 1923. Serial No. 679,803.

This invention relates to water-tube boilers of the type wherein two upper steam-and-water drums and two lower water drums are connected by vertically and diagonally disposed water tubes whereof the vertical tubes 5 constitute down comers and the diagonal tubes constitute up comers, the whole affording a continuous water circulating path. In such boilers, as heretofore constructed, the 10 major flow of water is through the diagonal tube banks, and in consequence a restricted flow occurs in the vertical banks, thus producing an irregular circulation which results in low boiler efficiency and also causes 15 undue agitation of the water in the steam-and-water drums. Moreover, the resulting irregular expansion and contraction of the tubes of the respective tube banks cause the separation of the tube connections from the 20 drums.

To overcome these objections is the object of my invention, and to that end the invention, generally stated, comprises a boiler of the type mentioned having the up-comer and 25 down-comer elements of equal water capacity, and having baffles so constructed and arranged in relation to the tube banks and the drums that an effective distribution of the gases throughout the heating surfaces is 30 ensured.

The invention also comprises a novel arrangement of tube banks whereby the flow of water from each lower drum is divided into two streams which are directed to both 35 upper drums, said banks being so arranged as to present a maximum heating surface with consequently high over-all efficiency.

The invention also comprises features of construction and combinations of parts 40 which will be hereinafter described and claimed.

Referring to the drawing, which is a longitudinal vertical section of a marine boiler illustrative of my invention, 1 designates the 45 casing; 2 the furnace, and 3 the stack.

4, 5 designate two transverse steam-and-water drums, and 6, 7 two water drums located directly beneath the respective steam-and-water drums.

50 8 designates a bank of vertically-disposed water tubes connecting the drums 4, 6; and 9 designates a bank of similar tubes connecting the drums 5, 7.

10, 11 designate two diagonally-disposed 55 banks of water tubes, whereof one bank 10

connects the drums 6, 5, and the other bank 11 connects the drums 7, 4.

12, 13 designate two banks of diagonal tubes whereof one bank 12 connects the drums 4, 6, and the other bank 13 connects 60 the drums 5, 7.

The crossing portions of the tubes of the respective diagonal banks 10, 11 alternate with each other, and the tubes of each bank 12, 13 are arranged to alternate with the 65 lower portions of the tubes of the adjacent diagonal bank and also with the upper portions of tubes of the adjacent vertical bank, said tubes 12, 13 being reversely curved at their respective ends in a manner to enter 70 the respective lower and upper drums.

The tubes of the respective banks 8, 9 are equal to each other in number and area; the tubes of the respective banks 10, 11 are equal to each other in number and area, and the 75 tubes of the respective banks 12, 13 are equal to each other in number and area; the combined capacity of each pair of banks 10, 12 or 11, 13 being equal to the capacity of each vertical bank. Consequently there 80 is established and maintained a uniform uninterrupted water path to and from the respective drums, since the volume of water delivered by the down comers to the respective lower drums corresponds with that delivered by the up-comers to the respective upper drums.

14 designates superheater tubes extending from the steam spaces of the respective drums 4, 5 to a centrally-disposed transverse 90 header 15 from which the steam is withdrawn for service.

Overlying the outer rows of tubes of the respective diagonal banks 10, 11, and intersecting the planes of the respective tubes 12, 95 13 located in the spaces between the respective water drums and the crossing tube portions, are oppositely-inclined baffle walls 16; and spaced laterally of and above these walls and parallel therewith, or substantially so, 100 are the outer inclined members 17 of an M-shaped baffle structure. The lower portions of the members 17 intersect the planes of several of the adjacent vertical tubes and also the tubes 12, 13, and the upper portions 105 of such members intersect the planes of the respective diagonal tube banks 10, 11. The shorter members 18 of the baffle structure constitute a V-shaped arch that overlies the outer tubes of the respective diagonal tube 110

banks at and adjacent the angle of intersection of their crossing portions.

The oppositely-inclined baffle walls 16 provide, directly above the furnace chamber, a 5 primary heat pass having upwardly converging side walls which serve not only to direct the hot gases against the lower drums and longitudinally of the lower portions of all the up-comer tubes, but also toward and 10 among the crossed portions of the two diagonal tube banks 10, 11, thus ensuring the maximum action of the heat upon the up-comers to effect and maintain the rapid upward flow of the water from the lower to the 15 upper drums. The gases pass above and divide to the outer sides of the respective baffle walls 16 in a manner to impinge with a cross flow against the adjacent portions of the respective up-comers below the baffle 20 members 18, and are then directed downwardly through the secondary passes formed between the walls 16 and the baffle members 17, flowing thence to and among the respective tube banks, and also in contact with the 25 water drums. The gases then flow upwardly and above the M-baffle structure so as to impinge most effectively against and pass amongst the opposing upper portions of the up-comers and down-comers and also against 30 the steam-and-water drums; thence flowing against and amongst the superheating tubes, and escaping, finally, through the stack. The course of the hot gases is indicated by the 35 long arrows. By directing the gases in and through the devious course shown and described a continuous upward circulation of the water through the diagonal tube banks, and a corresponding downward flow of 40 water through the vertical tube banks, are established and maintained; and since the up-comers are equal in water capacity to the down-comers there is ensured a uniform and unrestricted circulation of the water through the tube area, thus producing a boiler having 45 extensive heating and water capacity and at the same time reducing to a minimum the agitation of the water in the steam-and-water drums even at high ratings. By 50 reason of the rapid and uniform circulation of the water throughout the boiler, and the described course of the gases, contraction and expansion of the tubes are at all times equal, thus preventing separation of the tube connections from the drums.

55 I claim—

1. A water-tube boiler comprising two upper steam-and-water drums, two lower water drums, two diagonal banks of crossing up-comer tubes having corresponding water capacity and whereof each bank connects a lower water drum with the remote upper steam-and-water drums, and the tubes of one bank are interspersed with those of the other bank, a bank of up-comer tubes connecting 60 each lower drum with the adjacent upper

drum and being equal in capacity to each bank of diagonal up-comer tubes, and a bank of down-comer tubes connecting each upper drum with the adjacent lower drum and being equal in capacity to two adjacent banks 70 of up-comer tubes, baffle walls located adjacent the upper portions of the respective diagonal banks in the spaces between the respective water drums and the crossing portions of the tubes of said diagonal banks, 75 and a baffle structure comprising inclined members spaced laterally of and above said walls and extending across the planes of the respective up-comer banks, and also an arch member covering the outer tubes of the said 80 diagonal banks adjacent their angle of intersection.

2. In a water-tube boiler having two upper steam-and-water drums, two lower water drums, two banks of tubes connecting the upper and lower drums at each side of the boiler, one of said banks constituting up-comers and the other bank constituting down-comers having double the capacity of the up-comers, a bank of diagonal up-comer 90 tubes connecting the lower drum at one side with the upper drum at the other side of the boiler, and a bank of diagonal up-comer tubes connecting the other lower drum with the other upper drum, said diagonal banks 95 having corresponding water capacity and each bank being equal in capacity to a bank of the first-named up-comer tubes, the crossing portions of the diagonal tube banks being interspersed with each other, baffle walls 100 covering the outer rows of tubes of the respective diagonal banks in the spaces between the respective water drums and the crossing portions of the tubes, and a baffle structure comprising inclined members 105 spaced laterally of and above the said walls and extending across the planes of the respective diagonal banks, and also an arch member connecting the upper ends of the 110 said inclined members and covering the outer tubes of the latter banks at and adjacent their angle of intersection.

3. In a water-tube boiler having two upper steam-and-water drums, two lower water drums, two banks of tubes connecting the upper and lower drums at each side of the boiler, one of said banks constituting up-comers and the other bank constituting down-comers having double the capacity of the up-comers, a bank of diagonal up-comer 115 tubes connecting the lower drums at one side with the upper drum at the other side of the boiler, a bank of diagonal up-comer tubes connecting the other lower drum with the other upper drum, said diagonal banks having corresponding water capacity and each bank being equal in capacity to a bank of the first-named up-comer tubes, the crossing portions of the diagonal tube banks being 120 interspersed with each other, a header, and 125 130

- superheater tubes leading thereto from the steam spaces of the upper drums, baffle walls covering the outer rows of tubes of the respective diagonal banks in the spaces between the respective water drums and the crossing portions of the tubes, and a baffle structure having inclined members spaced laterally of and above the said walls and extending across the planes of the respective diagonal banks, and also an arch member connecting the upper ends of the said inclined members and covering the outer tubes of the latter banks at and adjacent their angle of intersection. 5
- 15 4. In a water-tube boiler, two upper steam-and-water drums and two lower water drums, all included in a water circulating path wherein the water before passing from one steam-and-water drum to the other 10 steam-and-water drum is constrained to pass through one of the water drums, said path also including two diagonal banks of crossing up-comer tubes having corresponding water capacity and whereof each bank connects a lower water drum with the remote upper steam-and-water drum, and the tubes of one bank are interspersed with those of the other bank, a bank of up-comer tubes connecting each lower drum with the adjacent upper drum and being equal in capacity to each bank of diagonal up-comer tubes, a bank of down-comer tubes connecting each upper drum with the adjacent lower drum and being equal in capacity to two adjacent banks of up-comer tubes, baffle walls adjacent the upper portions of the respective diagonal banks in the spaces between the respective water drums and the crossing portions of the tubes of the diagonal banks, baffle members spaced laterally of and above the said walls and extending across the planes of the respective up-comer banks, and an arch member for the said diagonal banks adjacent their angle of intersection. 20 25 30 35
- 15 4. In a water-tube boiler, two upper steam-and-water drums and two lower water drums, all included in a water circulating path wherein the water before passing from one steam-and-water drum to the other 10 steam-and-water drum is constrained to pass through one of the water drums, said path also including two diagonal banks of crossing up-comer tubes having corresponding water capacity and whereof each bank connects a lower water drum with the remote upper steam-and-water drum, and the tubes of one bank are interspersed with those of the other bank, a bank of up-comer tubes connecting each lower drum with the adjacent upper drum and being equal in capacity to each bank of diagonal up-comer tubes, a bank of down-comer tubes connecting each upper drum with the adjacent lower drum and being equal in capacity to two adjacent banks of up-comer tubes, baffle walls adjacent the upper portions of the respective diagonal banks in the spaces between the respective water drums and the crossing portions of the tubes of the diagonal banks, baffle members spaced laterally of and above the said walls and extending across the planes of the respective up-comer banks, and an arch member for the said diagonal banks adjacent their angle of intersection. 20 25 30 35 40 45

Signed at New York in the county and State of New York this 7th day of December A. D. 1923.

HENRY CHARLES BADY.
